UNITED STATES PATENT OFFICE.

CHARLES AUTH, OF NEW YORK, N. Y., ASSIGNOR TO EMMA LOUISE AUTH, OF BROOKLYN, NEW YORK.

ANNUNCIATOR DROP.

Application filed May 16, 1919. Serial No. 297,696.

The invention has for an object to provide an annunciator drop which will be effectively locked in both set and reset positions, and yet will be dependable in operation from one 5 position to another, and operate with a small amount of current.

Another object is to so construct the device that it may be readily assembled or taken apart manually, without requiring the use 10 of special tools for this purpose.

Another object is to provide a construction such that the annunciator as a whole may be readily placed in or removed from operative position.

15 Another object of the invention is to provide a magnetic circuit in the annunciator such that losses of energy due to stray lines of force will be minimized as much as possible.

20 Further objects and advantages will be in part obvious and in part specifically pointed out in the description hereinafter contained in which is disclosed one embodiment of the invention; such embodiment however, is to be considered merely as illustrative of its principle. In the drawings:—

Fig. 1 is a plan view of a device made in accordance with the invention.

Fig. 2 is a side view of the same showing 30 the indicator support in set position.

Fig. 3 is a perspective view showing the indicator support detached.

The device as a whole is mounted upon an insulating base block 1, carrying suitable 35 members for supporting the setting and resetting coils. In the present instance, a pair of end plates 2 and 3 of non-magnetic material such as brass are employed, together with separate setting and resetting coils 4 and 5, the cores 6 and 7 of which are pressed through holes in the end plates 2 and 3. The block 1 is provided on its end faces with projections 8 which are similarly pressed through holes 9 in the end plates 2 and 3.

45 It is preferred to supplement the core 7 of the resetting coil 5 with an outer magnetic member, which in the present instance is in the form of a U-shaped piece of soft steel or iron having a base 10 which overlies 50 the end plate 2, and sides 11 and 12 which are pressed through holes in the end plates 2 and 3.

With a structure of the character above described, the drop may be readily assembled 55 or disassembled at any time merely by pull-

ing apart the end plates 2 and 3, or movement of the same endwise of the coils, since all of the parts are held together only by press fits as above described.

Also, the drop preferably is so connected in circuit that it may be quickly placed in or removed from operative position without detachment of screws or the like. This is accomplished in the present form by providing the block 1 with a plurality of quick 60 detachable connectors 13, designed to fit into sockets 14 carried by any suitable wall fixture (not shown), and said connectors are joined respectively to the setting and resetting windings in such a way that proper circuit connections will be made to the windings when the connectors are in operative position, as will be readily understood. Although the drop may be used in any position, it is ordinarily disposed horizontally 70 and in such position the connectors 13 support it as a whole.

The indicator support, in the form illustrated, consists of a yoke 15 having side arms 16 and 17 which are pivoted upon studs 18 fixed to the end plates 2 and 3. The side arms 16 and 17 are provided with armatures 19 and 20 located respectively adjacent the cores of the coils 4 and 5, each of the armatures being so shaped that the magnetic pull draws the main body of the armature up to a position opposite the end of the respective coil core, when the coil is energized. The side arm 16 of the indicator support may also be provided with a heel 21 having shoulders 22 and 23 which cooperate with a locking device to hold the indicator in set or reset position, as the case may be. 85

In the form illustrated, a locking armature 24 is provided with a detent 25 which is adapted to engage selectively with the shoulders 22 and 23, and thus hold the indicator support in the position to which it has last been moved, when the coils 4 and 5 are de- 90 energized.

The locking armature 24 preferably includes an angle shaped spring strip having one leg 26 bowed inwardly between undercut notches 27 in the ends of the end plates 2 and 3, and its remaining leg 28 extending across one end of the cores of both coils 4 and 5. As shown, a small screw 29 upon the end plate 3 limits the movement of the locking armature 24 toward the coils so as to prevent sticking, and the outer end of the 105 110

locking armature is extended through a hole 30 in the side 12 of member 10, so as to limit the outward movement of the locking armature.

5 The locking armature 24 is thus moved to disengage detent 25 from the indicator support, whenever either of the coils 4 and 5 is energized. If the indicator support be in reset position for instance, the energization 10 of coil 4 will cause the locking armature 24 to be drawn in so as to release detent 25 from shoulder 23, and armature 19 will be drawn up to overlie the end of core 6, so as to hold the indicator support in set position 15 as long as current continues to pass through coil 4. As soon as current ceases to pass through coil 4, the locking armature 24 will be released, and detent 25 will engage shoulder 22 thus holding the indicator support in set position. The inwardly bowed shape of the leg 26 of the spring strip effects a quickness of action in the locking armature which insures that it will lock the indicator support in proper position at all 20 times.

25 It is preferred to balance the indicator supporting yoke in such a way that it will naturally assume a position intermediate set and reset positions, the set position being 30 preferably substantially to one side of the position which the yoke would naturally occupy, and the reset position being slightly to the other side of said natural position. With such a construction, if the indicator support be in set position, when the resetting coil 5 will be energized to release detent 25 from shoulder 22, the action of gravity will supplement the pull of core 7 upon armature 20 in drawing down the indicator 35 support to reset position, and such support will tend to swing by its natural position sufficiently to lock the detent 25 beneath shoulder 23, and thus hold the indicator support in reset position. However, if the drop 40 is not horizontal, as might happen in ship installations for instance, or if the locking armature 24 has not been released by the core 7 at the time when shoulder 23 has reached a position above the detent 25, the 45 pull on armature 20 by the core, will insure that the shoulder reaches a position above the detent 25 and is maintained in such position until the locking armature 24 is released to permit detent 25 to engage under shoulder 23. Furthermore, if the setting coil 4 be then energized to raise the indicator support to set position, the action of 50 gravity will supplement the pull of core 6 upon armature 19 to start this setting movement, since the indicator support has moved somewhat beyond its natural position when being reset. The indicator support therefore, does not have to start from a dead stop in moving from either position to the other, 55 but yet the action of gravity in each instance

is combined with an electromagnetic pull so as to make both movements positive.

60 In annunciator drops, it often happens that the weak currents used in the coils are not sufficient to insure proper movement of the indicator support, owing to losses through stray lines of force. To prevent such losses a magnetic bar 31 extending between opposite faces of the coils may be employed, so as to provide a return path of 65 high conductivity for the lines of force. In the present form such bar connects the side arms 16 and 17 of the indicator supporting yoke, and will form a return path for the lines of force in regard to both coils. As 70 shown, however, the magnetic bar 31 forms a shorter return path for the resetting coil 5, since such coil is ordinarily of higher resistance than the setting coil and thus naturally weaker in its action.

75 It is desirable that the indicator support be so formed that it may be readily detached from the end plates 2 and 3 while the latter are in operative position, so as to facilitate disassembling of the drop without the use 80 of special tools. For this purpose the magnetic bar 31 may be made sufficiently springy to permit the side arms 16 and 17 of the yoke to be separated away from studs 18, and the side arms may be detachably connected to the indicator frame 32. As shown, the side arms 16 and 17 are provided with cross pieces 33 having notched sides 34, and the bottom of the indicator frame 32 is cut out to provide openings 35, the outer walls 95 36 of which are spaced a sufficient distance to receive snugly the notched sides 34 of the cross pieces 33. Notches 37 are also cut in the walls 36, a slight distance from the outer ends of the openings 35, so that the cross 100 pieces 33 can be inserted through the notches 37, and their undercut sides 34 engaged with the side walls 36a of the openings 35. Spring 105 tongues 38, left in the base of the frame 32 after the openings 35 have been cut, which 110 have been bent back during the insertion of cross pieces 33 into slots 37, may then be bent back even with the remainder of base of the frame 32 so as to hold cross pieces 33 firmly against the ends of the openings 115 35.

120 In the present construction, movement of the indicator support toward set position is limited by a stop 41, struck up from the side plate 3, and the engagement of magnetic bar 31 with the bottom of the side plates 2 and 3, stops the indicator support at the proper point, in movement toward reset position.

125 The annunciator drop will be understood as employed behind a suitable partition 39 having a window 40 through which the indication 42, received within the frame 32, is visible when the indicator support is in set position.

While a specific form of the invention has been described, it is obvious that many changes may be made without departing from the spirit of the invention as defined in the following claims.

I claim:

1. An annunciator drop comprising substantially horizontal setting and resetting coils, an indicator support pivoted adjacent thereto, and having armatures movable respectively by the coils, said support being balanced to naturally occupy a position between its set and reset positions, whereby the action of gravity supplements the electromagnetic pull in both setting and resetting positions.

2. An annunciator drop comprising a pivoted indicator support, electromagnetic means for urging said support both to set and reset positions, said support being balanced to naturally occupy a position between its set and reset positions, whereby the action of gravity supplements the electromagnetic pull in both setting and resetting positions.

3. An annunciator drop comprising a pivoted indicator support, electromagnetic means for urging said support to set position, said support being balanced so that its set position is substantially above its natural position, and its reset position being slightly at the other side of natural position, automatic locking means for holding said support in set and reset positions, the locking means being disengaged upon energization of said electromagnetic means.

4. An annunciator drop comprising substantially parallel setting and resetting coils, a U-shaped indicator yoke pivoted to swing on an axis substantially parallel to the longitudinal axes of the coils, said yoke having armatures at one of the legs respectively adjacent the cores of the setting and resetting coils.

5. An annunciator drop comprising substantially parallel setting and resetting coils, a U-shaped indicator yoke pivoted between said coils to swing on an axis substantially parallel to the longitudinal axes of the coils, said yoke having armatures at one of the legs respectively adjacent the cores of the setting and resetting coils.

6. An annunciator drop comprising substantially parallel setting and resetting coils, an indicator yoke pivoted to swing on an axis parallel to the longitudinal axes of the coils, said yoke having armatures respectively adjacent both ends of the cores of the setting and resetting coils.

7. An annunciator drop comprising substantially parallel setting and resetting coils, an indicator yoke pivoted to swing on an axis parallel to the longitudinal axes of the coils, said yoke having armatures respectively adjacent both ends of the cores

of the setting and resetting coils, and having a magnetic bar extending between the opposite ends of the coils so as to form a return path for the lines of force, in regard to either coil.

8. An annunciator drop comprising setting and resetting coils, an indicator support movable by either of said coils, and a locking armature having means for holding said support in set and in reset positions when the coils are deenergized, said armature being influenced by both coils so as to release said support when either coil is energized, and being interposed between said coil ends and parts on the indicator support which overlie the ends of the coils.

9. An annunciator drop comprising setting and resetting coils disposed side by side, a locking armature across one end of both coils, an indicator support movable by either of said coils and having parts interlocking with said armature to hold the support either in set or reset position when the coils are deenergized, said armature being interposed between said coil ends and said parts of the indicator support.

10. An annunciator drop comprising setting and resetting coils disposed side by side, a locking armature comprising an angle shaped spring strip having one leg bowed inwardly across one side of one of said coils, and its other leg extending across one end of both coils, an indicator support movable by either of said coils, said support and armature having parts interlocking to hold the support either in set or reset position when the coils are deenergized.

11. An annunciator drop comprising setting and resetting coils disposed side by side, a locking armature comprising an angle shaped spring strip having one leg bowed inwardly across one side of one of said coils and its other leg extending across one end of both coils, an indicator support yoke pivoted between the coils, said yoke being provided with armatures movable respectively by the coils, and having an arcuate heel provided with shoulders adapted to engage selectively with a lug on said locking armature to hold the yoke in set or reset position when the coils are deenergized.

12. An annunciator drop comprising a movably mounted indicator support, a coil adapted to move said support when energized, said indicator support being provided with a magnetic bar extending between opposite ends of said coil, so as to form a return path for the lines of force.

13. An annunciator drop comprising a movably mounted indicator support, setting and resetting coils disposed adjacent the same and each adapted to move said support when energized, said indicator support being provided with a magnetic bar extending between opposite ends of said coils, so as to

form a return path for the lines of force, in regard to either coil.

14. An annunciator drop having setting and resetting coils disposed side by side, end plates supporting said coils by means of holes through which the cores of the coils are pressed, whereby the coils may be dismounted by movement of the plates end-wise of the coils, alined studs carried by said plates, and an indicator supporting yoke pivoted on said studs, said yoke being sufficiently springy to enable the same to be placed on or removed from said studs while the plates are in normal position.
15. An annunciator drop having setting and resetting coils disposed side by side, end plates supporting said coils by means of holes through which the cores of the coils are pressed, a base block carrying terminal connections for the coils and having portions on its ends adapted to interengage with adjacent parts of said end plates, whereby the coils may be dismounted by movement of the plates end wise of the coils, and an indicator support pivoted to said end plates, said support being detachable from said plates while the latter are in operative position.
16. An annunciator drop having setting and resetting coils disposed side by side, end plates supporting said coils, an indicator supporting yoke pivoted upon said end plates and having armatures respectively adjacent ends of the cores of the coils, and a locking armature for said yoke extending between said armatures and said core ends and having means for holding the yoke in either set or reset position when the coils are deenergized.
17. An annunciator drop having setting and resetting coils disposed side by side, end plates supporting said coils, an indicator supporting yoke pivoted upon said end plates and having armatures respectively adjacent ends of the cores of the coils, and a

locking armature for said yoke extending between said armatures and said core ends and having means for holding the yoke in either set or reset position when the coils are deenergized, said armature comprising an angle shaped spring strip having one arm bowed inwardly between the ends of the end plates.

18. An annunciator drop having a movably mounted yoke provided with side arms, each having at one end a cross piece with notched ends, an indicator carrying frame having its bottom cut away to provide slots adapted to receive said cross pieces and yieldable tongues adapted to be bent to hold said cross pieces in position.

19. An annunciator drop having setting and resetting coils, an indicator support having armatures respectively adjacent the cores of said coils, and a locking armature for the indicator support, one of said coils being provided with an outer magnetic member adapted to supplement the core in attracting said armatures.

20. An annunciator drop having setting and resetting coils disposed side by side, end plates adapted to support said coils, an indicator support pivoted to said end plates, and a locking armature for the indicator support, the reset coil being provided with an outer U-shaped magnetic member passed through said end plates and adapted to supplement the core in attracting said armature.

21. An annunciator drop comprising a pivoted indicator support, electromagnetic means for urging said support to set position, said support being balanced so that its set position is substantially above its natural position, and its reset position being slightly at the other side of natural position.

In testimony that I claim the foregoing, I have hereunto set my hand this 28th day of April, 1919.

CHARLES AUTH.
